Int. Cl. D26—05

U.S. Cl. D48—2

FIG. 1 is a perspective view of a lamp embodying my new design;

FIG. 2 is a front elevational view thereof;

FIG. 3 is a side elevational view thereof;

FIG. 4 is a bottom plan view thereof.

The characteristic features of my design reside in the configuration of the base.

I claim:

The ornamental design for a lamp, as shown and described.
